UNITED STATES PATENT OFFICE.

MATT WILLIAM KOSKI, OF COSMOPOlis, WASHINGTON.

NEUTRALIZER FOR GOVERNOR-CONTROLLED INDICATORS.

Application filed November 5, 1921. Serial No. 513,114.

To all whom it may concern:

Be it known that I, MATT WILLIAM KOSKI, a citizen of the United States of America, and resident of the city of Cosmopolis, in Grays Harbor County, State of Washington, have invented certain new and useful Improvements in Neutralizers for Governor-Controlled Indicators, of which the following is a specification. My invention relates to governor-controlled indicating devices such as a recording speedometer, and particularly to means for neutralizing the effect on such devices of sudden jolts and jars.

In recording speedometers, particularly where intended for automobiles, the sensitive working parts are at times subjected to severe shocks, which tend to move the indicator too far or too little in one direction, and thus to cause a false indication.

It is my object to provide means whereby such shocks may be neutralized, to the end that the indication given may always be in any suitable type, and an indicator which substantially exact accordance with the speed of the vehicle upon which it is mounted.

Other objects are to provide a neutralizing device of the character described which will be simple, cheap to make, and which will require no attention while in use. My invention comprises those novel parts and combinations thereof which are shown in the accompanying drawings, described in the specification, and particularly defined by the claims terminating the same.

In the accompanying drawings I have shown my invention in a form which is now preferred by me, and have shown it associated with a speed recording device of the character shown in my co-pending application for patent Serial No. 492,313. This, however, is for purposes of illustration only, and serve to dampen or neutralize the effect as obviously my neutralizing device may be used with many and various types of devices included in the general term "governor-controlled indicating devices."

Figure 1 is a sectional view through my recording speedometer showing the neutralizing device in elevation.

Figure 2 is an elevation of my neutralizing device.

Figure 3 is a section substantially on line 3-3 of Figure 2, and Figure 4 is a section through the medium of the neutralizing device on line 4-4 of Figure 2.

The general features of the recording

the influence of a speed responsive device such as the governor ball or ring 3. The marking point 10 is placed in contact with a sheet 4 upon which the record is made and which winds from a reel 41 upon a second reel 42. The paper is suitably fed forward positively, as by the sprocket wheel 40. It is to be understood, of course, that the particular constructions of the recording device and the governor form no part of this present invention and are described merely for purposes of better illustration.

The essential elements are a speed responsive device as, for instance, a governor of the type, and an indicator which is controlled in its position by this governor.

My invention comprises those novel parts the neutralizing device includes a clutch and combinations thereof which are shown in the accompanying drawings, described in the governor and to the indicator and which serves to transmit to the indicator all ordinary variations in the governor's position.

In the accompanying drawings I have shown my invention in a form which is now preferred by me, and have shown it associated with a speed recording device of the character shown in my co-pending application for patent Serial No. 492,313. This, however, is for purposes of illustration only, and serve to dampen or neutralize the effect as obviously my neutralizing device may be used with many and various types of devices included in the general term "governor-controlled indicating devices."

The governor 3 is mounted upon the shaft 31 which may be rotatable from a suitable source of power which is variable with the speed of the vehicle upon which the indicator is mounted, as, for instance, its wheel.

The sleeve 2 is mounted also upon the shaft 31 for axial movement. A governor link 32 connects the governor 3 and the sleeve 2.

Figure 3 is a section substantially on line 3-3 of Figure 2, and Figure 4 is a section through the medium of the neutralizing device 5. The neutralizing device 5 is herein shown as made in the form of a pair of semi-

circular elements 50 and 51 which encircle the shaft 31. The elements 50 and 51 are suitably suspended from the lower end of the sleeve 2, through the medium of a link 25 for each of the members 50 and 51. A spring or springs 52 maintain the clutch elements 50 and 51 spaced apart and prevent their gripping the shaft 31 ordinarily. These springs may be positioned at any 10 suitable point. They are sufficiently strong to transmit any ordinary force from the governor to the indicator, but are weak enough to permit the approach of the clutch elements 50 and 51 and their gripping upon 15 the shaft 31 in case of an extraordinary force being communicated to them from the governor.

The governor link 32 is not connected directly to either of the clutch elements 50 or 51 but is connected thereto through the medium of a lever 6 pivoted at 65 upon one of the clutch elements, as 51, and through a link 60 pivoted at 62 upon the clutch element 50 and at 61 upon the clutch element 25 51.

A fulcrum member, which is an integral part of the link 60, has two bearings upon the link 6 at spaced points between its ends. The link 6 is provided between its ends with 30 a socket or slot 63 within which lies the fulcrum member. One end 66 of this fulcrum member lies toward the pivot 65 from a line connecting the two pivots 61 and 62. The other end, 67, of the fulcrum member lies towards the swinging end of 35 the link 6 from such a line. The mechanism described may be employed single if desired, but I prefer that it be duplicated upon opposite sides of the shaft 31.

As the shaft 31 rotates, the governor 3, the sleeve 2, and the neutralizing device 5 rotate with it. Such rotation tends to throw the governor 3 into a plane normal to the axis of the shaft 31. Such movement of the 40 governor, communicated through the governor link 32 to the sleeve 2, tends to move the sleeve axially. The connection to the sleeve 2, however, is through the lever 6 and link 60 to the clutch elements 50 and 51 and 45 thence through the links 25 to the sleeve 2. The springs 52, as stated, are sufficiently strong to resist the attempt of ordinary force to cause approach of the elements 50 and 51. However, if a sudden extraordinary 50 force tends to throw the governor ball more nearly into a plane normal to the axis of rotation, for instance, the tendency of the governor link 32 is to move upward. This movement is communicated through the 55 lever 6 to the fulcrum 67. This then tends to bring the pivot points of the links 60 more nearly into a line parallel with the axis of the shaft 31 and overcomes the springs 52, at least to the extent of the force applied.

60 65 This movement causes approach of the

clutch elements 50 and 51 and they are caused to grip the shaft 31 thus to prevent axial movement of the neutralizing device and the sleeve 2 upon this shaft. Similarly a movement of the governor tending to pull 70 downward upon the connecting link 32 will react through the lever 6 upon the fulcrum 66 to produce the same result in substantially the same manner. The result is that sudden shocks upon the governor cause the 75 neutralizing device to grip the shaft 31 and to prevent axial movement of the sleeve 2, and consequently the indicator 1 is not affected thereby. During all of the time that the elements 50 and 51 grip the shaft 80 31 all parts are rotating with the shaft. When the shock of the governor's sudden movement is expended, the springs 52 again overcome the tendency to grip the shaft, and the device again becomes responsive to 85 ordinary movements of the governor.

It will be noticed that clutch elements 50 and 51 form one member of the clutch, the other member being the shaft 31. As the clutch elements 50 and 51 are axially bodily 90 movable upon the shaft, they may be taken as the movable member of the clutch, while the shaft, though rotatable, is yet fixed relative to the elements 50 and 51, and may be described as the fixed clutch member. 95

What I claim as my invention is:

1. The combination with an indicating device and a governor controlling the actuation thereof, of means operable by a sudden jar to neutralize the effect thereof upon 100 said governor and indication device.

2. The combination with an indicating device, an axially-movable sleeve controlling said indicating device by its axial position, and a governor operatively connected to 105 said sleeve to control its axial position, of means for preventing movement of the sleeve under the influence of sudden movements.

3. A neutralizing device for a governor-controlled indicator comprising a clutch member adapted to be moved bodily relative to a complementary fixed clutch member by the governor, and means retaining said clutch members disengaged under the 115 application of normal working forces, said means permitting the engagement of said clutch members under the influence of extraordinary forces.

4. A neutralizing device for a governor-controlled indicator comprising a shaft forming a fixed clutch member, a complementary clutch member axially movable upon said shaft in accordance with changes in the governor's position, and means retaining said clutch members disengaged under the application of normal working forces, said means being yieldable to permit the engagement of said clutch members under 125 the influence of extraordinary forces. 130

5. A neutralizing device for a governor-controlled indicator comprising a rotatable shaft, a split sleeve axially movable upon said shaft in accordance with changes in 5 the governor's position, a spring normally separating the ends of said sleeve, said spring being yieldable only under the application of extraordinary force from the governor.
- 10 6. A neutralizing device for a governor-controlled indicator comprising a rotatable shaft, a split sleeve axially movable upon said shaft, a spring normally separating the ends of said sleeve, a lever pivoted at 15 one side of the split in said sleeve, a link connected to its opposite end for transmitting movements of the governor thereto, a clutch link connected to the sleeve at opposite sides of the split, said clutch link having fulcrum 20 engagement with said lever between its ends, whereby said spring is yieldable to permit gripping of the shaft by the sleeve upon the application of extraordinary forces through the governor link.
- 25 7. In combination, a shaft, clutch elements axially movable upon said shaft, a governor, actuating means connecting the governor and clutch elements to cause movement of the latter corresponding with movement of the governor, and yieldable means 30 for preventing gripping of the clutch elements upon the shaft under ordinary working forces, but yieldable to permit gripping under extraordinary forces.
- 35 8. In combination, a governor, a shaft, clutch elements axially movable upon said shaft, yieldable means normally preventing gripping of the clutch elements upon the shaft, a governor link connected to the governor, and means operatively connecting 40 said governor link and the clutch elements, and operable by a movement of the governor link of extraordinary force in either direction to overcome said yieldable means to permit gripping of the clutch elements 45 upon the shaft.
9. In combination, a fixed clutch member, a movable clutch member normally disengaged from the fixed clutch member, a clutch link movable to engage said clutch 50 members, two fulcrum points carried by said clutch link and spaced upon opposite sides of a line joining the links pivots, a lever engaging said fulcrums between its ends, and governor-controlled means for 55 moving said lever, thereby to cause engagement of said clutch members by movement in either direction of the governor-controlled means.
10. The combination with an indicating 60 device and a governor controlling the actuation thereof, of normally inactive means for damping the movement of said governor and indicating device, said damping means being operatively connected to the governor 65 to be actuated by sudden movements thereof.

Signed at Cosmopolis, Grays Harbor County, Washington, this 28th day of October, 1921.

MATT WILLIAM KOSKI.
